Primary Examiner — Ricky Pham(74) *Attorney, Agent, or Firm* — David M. Driscoll, Esq.**CLAIM**

The ornamental design for a baking sheet, as shown and described.

DESCRIPTION

FIG. 1 is a perspective view of a baking sheet;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is an enlarged cross-sectional view along line 8-8 of FIG. 2.

The portions shown in broken lines are included for illustrative purposes only and form no part of the claimed design.
